[57] CLAIM

The ornamental design for a radiator cover, as shown and described.

DESCRIPTION

FIG. 1 is a perspective view of the radiator cover of my design.

FIG. 2 is a top plan view of the radiator cover of FIG. 1.

FIG. 3 is a side elevational view of a radiator cover of FIG. 1, the opposite side elevational view being the same.

FIG. 4 is a bottom plan view of the radiator cover of FIG. 1; and,

FIG. 5 is a front elevational view of the radiator cover of FIG. 1, the rear elevational view being the same.
